UNITED STATES PATENT OFFICE.

ROBERT CARL RAHM, OF WYOMISSING, PENNSYLVANIA, ASSIGNOR TO READING VALVE AND FITTINGS COMPANY, OF READING, PENNSYLVANIA, A CORPORATION OF PENNSYLVANIA.

TESTING MACHINE FOR PIPE FITTINGS.

Application filed August 21, 1919. Serial No. 318,985.

To all whom it may concern:

Be it known that I, ROBERT CARL RAHM, a citizen of the United States, residing at Wyomissing, in the county of Berks and 5 State of Pennsylvania, have invented certain new and useful Improvements in Testing Machines for Pipe Fittings, of which the following is a specification.

My invention consists in improved mechanism for testing pipe fittings and the like by subjecting the same to determined hydraulic pressures, as fully described in connection with the accompanying drawings illustrating a preferred embodiment of the 10 several features thereof, which are clearly defined in the subjoined claims.

Fig. 1 is a sectional elevation on the line 1—1 of Fig. 3, of a machine embodying the complete invention and adapted particularly 15 for testing the fitting indicated in dotted lines.

Figs. 2 and 3 are corresponding side and plan views respectively.

Fig. 4 is a sectional plan view mainly on 20 the line 4—4 of Fig. 1, but partly on the line 4—4 of Fig. 5.

Fig. 5 is a sectional view of the pressure regulating device, taken on the line 5—5 of Fig. 3; and Fig. 6 is a cross-sectional view 25 of the same on the line 6—6 of Fig. 5.

Fig. 7 is sectional elevation, similar to Fig. 1, but indicating a modified construction.

The drawing indicates, in dotted lines, a 30 pipe fitting 10 in position for testing; said fitting resting upon a seating disc 11 on the head 12 of a fixed hydraulic cylinder 13, which latter depends between the two parts of a supporting frame 14—14. The interior 35 of the fitting is in communication with the pressure chamber 13^a of this cylinder 13, through a top opening 15 in the latter; and a closing-and-clamping mechanism for the fitting is carried by an enclosing cylinder 20 which is provided with packing 21 and moves exteriorly upon the fixedly supported 40 depending cylinder 13; the latter thus serving as a fixed plunger upon which the carrying cylinder 20 is moved.

As shown, this movable cylinder 20 is provided with a concentric inner cylinder 22, rising loosely into the cylinder 13 so as to form an annular chamber 23 for the latter to extend into more or less as the movable

cylinder is raised or lowered thereon, and this inner cylinder 22, which has a top closure 24, is simultaneously raised and lowered upon a centrally fixed column 25 provided with packing 26. The separate liquid chambers are thus provided for effecting movement of the combined cylinders 20—22; primarily the chamber 13^a, in which the pressure put upon admitted liquid is utilized to force said cylinders downward as desired during the operation of testing; and in addition the chamber 22^a in which light pressure may be independently employed to preliminarily set the closing-and-clamping mechanism for the placed fitting. Liquid admitted to chamber 13^a at 30; through piping 31 under control of a three-way valve 32, and which also fills the clamped fitting 10, is afterward subjected to a determined pressure for testing the latter as hereinafter described; while liquid independently admitted to chamber 22^a through the hollow column 25 and connecting piping 33, under control of a similar valve at 34, is utilized merely to reversely move the cylinder 20 as may be desired for clamping the fitting.

The closing-and-clamping mechanism, as shown, consists of a circularly arranged series of jointed levers attached to the movable cylinder 20 at 40 and 41 as shown, and provided with desired contacts for the fitting, which contacts are adapted to be forced against the latter in required direction by downward movement of said cylinder. The contacts 45, 45^a are secured to side levers 46, 46^a so as to be pressed against the horizontally aligned branch openings of the "cross" fitting indicated, while the contact 47 is secured to the top lever 48, which is connected by links 49 and 49^a to the respective side levers. Each of these contacts, as shown, consists of a closure plate adapted to seat against an interposed sealing disc 50 on the fitting, and an adjusting screw 51 carrying the same so as to permit of its being loosely set against the fitting. A valved air-vent 52 is provided in connection with the contact 47.

In a testing operation all of these contacts are simultaneously pressed against the fitting by the downward movement of the movable cylinder 20 under pressure exerted upon the operating medium admitted to chamber 13^a; which pressure is also exerted upon the

fitting, to which it is simultaneously admitted through opening 15.

To balance the weight of the movable clamping mechanism and conveniently 5 maintain the pivotally connected parts in symmetrical relation, I employ balance weights 55, connected by cords 56, running over pulleys 57, 58, to the side levers 46, 46^a; provision being also made for conveniently 10 raising or lowering the top lever so as to position the contacts for different fittings, by means of a handwheel shaft 60, operating through a belt 61 to turn the balance-weight pulleys as desired.

15 The pressure effecting means already referred to and separately shown in Figs. 5 and 6, comprises a pressing lever 65 provided with an adjustable weight 66 and connected to a pressure piston 67, which piston is movable in a vertically fixed cylinder 68 arranged in communication with the conduit 31 supplying liquid to chamber 13^a. The lever 65 is pivoted to a bracket 70 on said cylinder, and is adapted to maintain a 20 pressure, through piston 67, upon the liquid in chamber 13^a and fitting 10, as determined by the adjustment of the weight 66 thereon. The jaw-shaped end of lever 65 (Figs. 2, 4, 5) is shown as pivoted to the lower ends of a pair of links 73 which 25 carry at their upper ends a supporting collar 71, and the screw-threaded piston rod 67^a passes through the circularly-grooved hub of an adjusting wheel 72 engaging said 30 collar, so that the turning of said wheel will adjust the position of the piston 67 relative to the lever 65. The latter is normally supported in suitably raised position as by means of a cam 75 (Fig. 1), so that 35 the turning of said cam will release the lever and permit the weight 66 to depress it and exert the determined pressure on piston 67.

Referring to the showing of Fig. 1, it will 40 be understood that the balanced series of levers may be symmetrically adjusted so as to freely permit the placing of the fitting 10 upon the cylinder head 12, by turning the hand wheel shaft 60 as indicated; 45 the size of the fitting engaged being variable within determined limits, with corresponding adjustment of the projections of the several contacts 50. This adjustment, as shown, is further variable 50 by admitting fluid pressure to chamber 22^a through conduit 33, whereby the movable cylinder 20—22 may be raised as desired upon the fixed plunger 13 to facilitate the proper securing of the fitting 10; such pressure 55 in chamber 22^a being removed before applying the testing pressure in chamber 13^a.

After the fitting 10 is thus tightly secured, liquid is admitted through conduit 60 31, under ordinary head available, to the

chamber 13^a and the fitting 10, until the air is fully discharged through vent 52, when it is shut off; after which the release of the weighted lever 65 from its supporting cam 75 exerts the determined pressure upon the 70 contained liquid by pressing downward the piston 67. The liquid being practically incompressible this downward movement is normally very limited, but the adjusting means 72 permits of setting the pressure 75 piston 67 as desired relative to the pressure lever 65.

The indicated clamping and sealing means carried by the hydraulically moved element 20 may evidently be varied, as indicated, for instance, in Fig. 7, where the series of jointed levers 80, 81, 82 are particularly adapted for clamping and sealing an ell fitting 10^c. This fitting is shown as resting on the seating disc 11^c and its opposite end closed by sealing disc 50^c of a side contact 45^c adjustably supported in lever 82, and is maintained in position by contacts 85, 86 pivotally supported in socket 87. This socket is shown as pivoted at the meeting point 85 of two links 88 and 89, their opposite ends being pivoted respectively to levers 80 and 81, so that the contacts 85 and 86 will automatically adjust themselves to equalize their retaining pressure on the fitting 10^c. The bearing 41^c for lever 82 is fixed to the frame 14^c 14^c instead of to the cylinder 20^c and an adjusting screw 87 permits of raising or lowering the lever 82 so as to regulate it 90 for fittings of various sizes. 100

This figure also shows the hydraulic mechanism in simplified form, the means set forth for hydraulically adjusting the movable cylinder 20 to facilitate the proper setting of the clamping levers, being omitted. 105

The construction specifically set forth may be otherwise modified within the scope of the invention as defined in the claims.

What I claim is:

1. In a testing machine for pipe fittings and the like, an hydraulic plunger and cylinder one of which is fixedly mounted and provided with an apertured closing and supporting head for one branch of the fitting and the other of which carries a circular series of jointed closing and clamping levers, and balancing means for said jointed levers. 110

2. In a testing machine for pipe fittings and the like, an hydraulic plunger and cylinder one of which is fixedly mounted and provided with an apertured fitting supporting head and the other of which carries a circular series of levers jointed to determinely distribute the closing and clamping pressure. 120

3. In a testing machine for pipe fittings and the like, a fixedly supporting plunger having a fitting supporting head and a lon- 130

- 5 gitudinal liquid passage way therethrough, an hydraulic cylinder exteriorly movable on said fixed plunger, and jointed clamping means carried by said movable cylinder and 5 adapted to determinedly distribute the 45 clamping pressure.
4. In a testing machine for pipe fittings and the like, a fixedly supported plunger having a fitting supporting head and a lon- 50 gitudinal liquid passage way therethrough, an hydraulic cylinder exteriorly movable on said fixed plunger, a circular series of jointed closing and clamping levers carried by said movable cylinder, and weight bal- 55 ancing means for said jointed levers.
5. In a testing machine for pipe fittings and the like, a fixedly supported plunger having a fitting supporting head and a lon- 60 gitudinal liquid passage way therethrough, an hydraulic cylinder exteriorly movable on said fixed plunger, a circular series of jointed closing and clamping levers carried by said movable cylinder, and weight bal- 65 ancing adjusting means for said movable parts.
6. In a testing machine for pipe fittings and the like, a fixedly supported plunger having a fitting supporting head and a lon- 70 gitudinal liquid passage way therethrough, an hydraulic cylinder exteriorly movable on said fixed plunger, and fitting clamping and sealing means carried by said movable cylinder.
7. In a testing machine for pipe fittings and the like, a fixedly supported plunger having a fitting supporting head and a lon- 75 gitudinal liquid passage way therethrough, an hydraulic cylinder exteriorly movable on said fixed plunger, and a circular series of jointed clamping levers carried by said movable cylinder, certain of said levers being provided with fitting contacts.
8. In a testing machine for pipe fittings
- and the like, a fixedly supported plunger having a fitting supporting head and a lon- 80 gitudinal liquid passage way therethrough, an hydraulic cylinder exteriorly movable on said fixed plunger, and a circular series of jointed clamping levers carried by said movable cylinder, certain of said levers being provided with relatively adjustable fitting contacts.
9. In a testing machine for pipe fittings and the like, a fixedly supported plunger having a fitting supporting head and a lon- 85 gitudinal liquid passage way therethrough, a fitting clamping cylinder movable on said fixed plunger and provided with an inverted concentric inner cylinder, and a fixedly sup- 90 ported hollow plunger column extending into said inner cylinder and provided with a liquid passage way to the latter.
10. In a testing machine for pipe fittings and the like, a fixedly supported plunger having a fitting supporting head and a lon- 95 gitudinal liquid passage way therethrough, a fitting clamping cylinder movable on said fixed plunger and provided with an inverted concentric inner cylinder, and a fixedly sup- 100 ported hollow plunger column extending into said inner cylinder and independently controlled liquid conduits to said movable cylinder and hollow column respectively.
11. In a testing machine for pipe fittings and the like, an hydraulic plunger and cyl- 105 inder one of which is fixedly mounted and provided with an apertured fitting support- 110 ing head and the other of which carries clamping means adapted to determinedly distribute the clamping pressure, liquid sup- 115 plying means, and pressure applying means comprising a weighted lever and connected pressure piston.

In testimony whereof I affix my signature.

ROBERT CARL RAHM.
